UNITED STATES PATENT OFFICE.

MAX SZAPIAK, OF ST. MICHAEL, PENNSYLVANIA.

DESIGN FOR A CALENDAR-WATCH.

56,637.

Specification for Design.

Patented Nov. 16, 1920.

Application filed June 5, 1920. Serial No. 386,820. Term of patent 3½ years.

To all whom it may concern:

Be it known that I, MAX SZAPIAK, a citizen of Poland, and a resident of St. Michael, in the county of Cambria and State of Pennsylvania, have invented a new, original, and ornamental Design for a Calendar-Watch, of which the following is a specification, reference being had to the accompanying drawings, forming part thereof.

The figure is a front view of a calendar watch showing my new design.

I claim—

The ornamental design for a calendar watch as shown.

MAX SZAPIAK.
